UNITED STATES PATENT OFFICE.

ARTHUR A. McRAE, OF ATTLEBORO, MASSACHUSETTS.

DESIGN FOR A PIN, BROOCH, EMBLEM, OR SIMILAR ARTICLE.

46,651.

Specification for Design.

Patented Nov. 17, 1914.

Application filed September 23, 1914. Serial No. 863,236. Term of patent 7 years.

To all whom it may concern:

Be it known that I, ARTHUR A. McRAE, a citizen of the United States, residing at Attleboro, in the county of Bristol and State of Massachusetts, have invented a certain new, original, and ornamental Design for a Pin, Brooch, Emblem, or Similar Article, of which the following is a specification.

In the accompanying drawing which forms a part of this specification, the figure is a front view of an emblem embodying my design.

I claim:—

The ornamental design for a pin, brooch, emblem or similar article, as shown.

ARTHUR A. McRAE.
